UNITED STATES PATENT OFFICE

CLARA B. GREEN, OF MIDDLETOWN, DELAWARE.

COMBINED MATCH-BOX AND SMOKER'S SHIELD.

SPECIFICATION forming part of Letters Patent No. 540,307, dated June 4, 1895.

Application filed November 17, 1894. Serial No. 529,177. (No model.)

To all whom it may concern:

Be it known that I, CLARA B. GREEN, a citizen of the United States, residing at Middletown, in the county of New Castle and State 5 of Delaware, have invented a new and useful Combined Match-Box and Smoker's Shield, of which the following is a specification.

This invention relates to an improved device for containing matches and for shielding the flame thereof when it is desired to light a cigar or pipe in the open air, and when the wind is liable to extinguish the match.

The object of the present invention is to provide a simple and inexpensive match box 15 and smoker's shield combined which shall be capable of being folded into compact shape, adapting it to be carried in the pocket, said device being constructed in such manner that it may be quickly manipulated for giving access to the interiorly arranged match receptacle and extended so as to form a shield for protecting a lighted match.

Other objects and advantages of the invention will appear in the course of the subjoined 25 description.

The invention consists in certain novel features and details of construction and arrangement of parts, as hereinafter fully described, illustrated in the drawings and pointed out 30 in the claims.

In the drawings the details of my invention are fully illustrated, and therein—

Figure 1 represents a perspective view of my invention, showing it open and in position 35 for use as a shield; Fig. 2, a similar view showing the device closed and in the position assumed when at rest; Fig. 3, a longitudinal section taken through the device when closed or in the position of Fig. 2; Fig. 4, a cross-section taken through the device while closed; Fig. 5, a detail perspective illustrating the hinge connection between the several parts 40 of my device.

The reference numeral 1 indicates the back 45 or body portion of my improved match-box and shield, and this is to be formed of any suitable material, such as sheet metal or wood, and which has the four sides 2, 3, and 4. The back 1 is rectangular in shape, and the sides 50 2 and 3 are at the ends thereof; while the sides 4 are at the sides proper of the back.

Formed integral with or rigidly secured to the upper end of the side 3 is the plate 5, which extends parallel with the back 1, and inwardly to a point slightly beyond the center or middle of the back. This plate is of a width equal to the width of the back 1, and is securely fastened to the upper ends of the sides 4, for about two-thirds of its length, leaving its inner end disconnected from the 55 sides.

The inner end of the plate 5 is made capable of swinging, or more properly is provided with a second plate 6, which is hinged to the plate 5 by means of the hinges 7, and which 65 is capable of swinging on a horizontal axis for a purpose hereinafter explained. The inner or free end of the plate 6 is provided with a downwardly-extending flange 8, which is adapted to engage the back 1 when the plate 70 6 is swung downwardly, thereby forming a space inclosed by the plates 5 and 6 and back 1. In this space the matches are to be arranged, and by swinging the plate 6 on the hinge 7 their outer ends may be exposed, so 75 that they may be grasped and removed. The plate 5 has its outer side corrugated or fluted, so as to form a surface with the necessary roughness for permitting the firing of the matches. Thus the matches may be withdrawn from the space inclosed by the plates 5 and 6 and ignited by rubbing them over the 80 plate 5.

9 and 10 indicate, respectively, two swinging plates which are each provided with 85 hinges 11, by which they are connected to the respective sides 4, so as to be capable of swinging thereon; and the plates 9 and 10 are of a size equal to the size of the back 1. The plates 9 and 10 are capable of swinging so as 90 to lie parallel with the back 1, and so as to cover the space inclosed by the sides of said back and so as to lie over the plates 5 and 6. The side to which the plate 9 is hinged is lower than the opposite side, and this construction is provided in order that the plate 95 9 may lie under the plate 10 when both are folded over the back 1.

Hinged to the side 2 is the plate 12, which is of a width equal to the width of the back 100 1, and which has at its sides the flanges 13. The flanges 13 are one for each side of the

plate 12, and are of a width equal to the width of the sides 4. The plate 12 is adapted, when the device is folded, to swing horizontally and parallel with the back 1, and to lie directly 5 against the outer side of the plate 10, with its flanges 13 lying against the outer sides of the sides 4.

The extended position of my device is shown in Fig. 1, and there it will be seen that the plates 9 and 10 are moved so as to lie parallel 10 with the sides 4, and that the plate 12 is moved so as to extend parallel with the side 2. This places the flanges 13 in a position which 15 will permit them to overlap the front edges of the plates 9 and 10, thus making a tight connection and one which will prevent the passage of air during the use of the appliance. When folded, the plates 9 and 10 lie snugly 20 against each other and parallel with the back 1, and the plate 12 lies over the plate 10, as shown in Fig. 2 and as has been explained.

In using my invention the space inclosed by the plates 5 and 6 should be filled with matches, and, supposing that it is not desired 25 to use the device immediately, the plates 9, 10, and 12 should be folded in the position explained. When, however, it is desired to light a pipe or cigar, the plates 9 and 10 should be moved to the position shown in Fig. 1, and the 30 plate 12 moved to engage them, all of which has been explained. It will now be possible to swing the plate 6 so as to uncover the upper ends of the matches inclosed by the plates 5 and 6, and to withdraw and ignite a match. 35 The pipe or cigar may now be lighted by raising the device so that the pipe or cigar may be projected into the space between the plates 9, 10, and 12. This will enable the lighting to be performed without being interfered with 40 by the wind, all of which will be understood.

Various changes in the form, proportion and the minor details of construction may be resorted to without departing from the principle

or sacrificing any of the advantages of this invention.

45

Having described the invention, I claim—

1. A combined match box and smoker's shield comprising a rectangular back portion provided with a surrounding flange forming sides around its four edges, a plate 5 secured 50 to said flange at one side and extending inwardly to form a match receptacle, the plates 9 and 10 hinged to said flange on opposite sides and capable of folding upon each other, and the plate 12 hinged to said flange upon the remaining side and provided with oppositely disposed flanges 13 forming stops for retaining the sides 9 and 10 when swung into an extended position, substantially as described.

60

2. A combined match box and smoker's shield consisting of a rectangular back plate having sides 2, 3 and 4 extending around its four edges, a plate 5 secured to one of said sides and projecting inwardly in the plane of 65 the front edges of said sides to form a match receptacle, the plate 6 hinged to the plate 5 and forming a swinging door therefor, the plates 9 and 10 hinged to opposite sides of the back plate and capable of swinging into 70 parallel relation therewith or of assuming an extended position, and the plate 12 hinged to the remaining side of the back portion and provided with inwardly projecting flanges 13 capable of embracing the sides of the back 75 portion and also forming stops for engaging the edges of the plates 9 and 10 for limiting the outward movement thereof, substantially as described.

In testimony that I claim the foregoing as 80 my own I have hereto affixed my signature in the presence of two witnesses.
